UNITED STATES PATENT OFFICE.

MABELLE G. LOEW, OF NEW YORK, N. Y.

DESIGN FOR A TIRE TREAD-BLOCK.

52,331.

Specification for Design.

Patented Aug. 27, 1918.

Application filed May 2, 1916. Serial No. 95,005. Term of patent 3½ years.

To all whom it may concern:

Be it known that I, MABELLE G. LOEW, a citizen of the United States, residing at New York city, in the county of New York and State of New York, have invented a new, original, and ornamental Design for a Tire Tread-Block, of which the following is a specification, reference being had to the accompanying drawing, forming part thereof.

Figure 1 is a side elevation showing my design of the tire tread block.

Fig. 2 is a plan view thereof.

Fig. 3 is an end elevation.

I claim:

The ornamental design for a tire tread block, as shown.

MABELLE G. LOEW.

Witness:

ANNA V. DOYLE.
